(57) **CLAIM**

The ornamental design for a display screen console, substantially as shown and described.

DESCRIPTION

FIG. 1 is a front perspective view of a display screen console according to an embodiment of the present design.

FIG. 2 is a second perspective view of the display screen console shown in FIG. 1.

FIG. 3 is a front elevation view of the display screen console shown in FIG. 1.

FIG. 4 is a top plan view of the display screen console shown in FIG. 1.

FIG. 5 is a bottom plan view of the display screen console shown in FIG. 1.

FIG. 6 is a left side elevation view of the display screen console shown in FIG. 1.

FIG. 7 is a right side elevation view of the display screen console shown in FIG. 1.

FIG. 8 is a left side detail view of the display screen console shown in FIG. 1.

FIG. 9 is a right side detail view of the display screen console shown in FIG. 1.

FIG. 10 is a front detail view of the display screen console shown in FIG. 1.

FIG. 11 is a detail view of the display screen console shown in FIG. 1.

FIG. 12 is a detail view of the display screen console shown in FIG. 1.

FIG. 13 is a front perspective view of a display screen console according to another embodiment of the present design.

FIG. 14 is a second perspective view of the display screen console shown in FIG. 13.

FIG. 15 is a front elevation view of the display screen console shown in FIG. 13.

(Continued)

FIG. 16 is a top plan view of the display screen console shown in FIG. 13.

FIG. 17 is a bottom plan view of the display screen console shown in FIG. 13.

FIG. 18 is a left side elevation view of the display screen console shown in FIG. 13.

FIG. 19 is a right side elevation view of the display screen console shown in FIG. 13.

FIG. 20 is a left side detail view of the display screen console shown in FIG. 13.

FIG. 21 is a right side detail view of the display screen console shown in FIG. 13.

FIG. 22 is a front detail view of the display screen console shown in FIG. 13.

FIG. 23 is a detail view of the display screen console shown in FIG. 13; and,

FIG. 24 is a detail view of the display screen console shown in FIG. 13.

The even-spaced broken lines depict portions of the display screen console that form no part of the claimed design. The dot-dash broken lines depict the limits of the detail views and form no part of the claimed design.
